[57] CLAIM

The ornamental design for an inflated face-down pillow for a woman, as shown and described.

DESCRIPTION

FIG. 1 is a top, front and right side perspective view of an inflated face-down pillow for a woman showing my new design;

FIG. 2 is a top plan view thereof, the undisclosed bottom being identical in appearance;

FIG. 3 is a right side elevational view thereof, the undisclosed left side being a mirror image of that shown;

FIG. 4 is a rear end elevational view thereof; and

FIG. 5 is a front end elevational view thereof.

FIG. I

FIG. 2

FIG. 3

FIG. 4

FIG. 5
